UNITED STATES PATENT OFFICE.

JOHN CAMPBELL MACCALL MACLAGAN, OF GLASGOW, SCOTLAND.

PISTON AND PISTON-ROD FOR INTERNAL-COMBUSTION ENGINES.

1,346,041.

Specification of Letters Patent.

Patented July 6, 1920.

Application filed September 18, 1919. Serial No. 324,106.

To all whom it may concern:

Be it known that I, JOHN CAMPBELL MACCALL MACLAGAN, subject of the King of Great Britain and Ireland, and resident of 5 Glasgow, Scotland, have invented certain new and useful Improvements in Pistons and Piston-Rods for Internal-Combustion Engines, of which the following is the specification.

10 The invention relates to pistons and piston-rods for internal combustion engines of double-acting Diesel type.

The invention has primarily for its object to provide an improved piston having 15 its under (or inner) side formed to the contour of the combustion space, substantially filling it when at that end of the stroke, and provided with an internal supplementary combustion space into which the fuel is directly delivered, the retardation of combustion owing to the flame being obstructed by 20 the piston-rod—as occurs in engines as hitherto generally constructed—being thus obviated. While this supplementary part of 25 the piston may be formed integrally with it, it is preferably formed on the upper end of the piston-rod, and the invention further relates to such a construction in which are also embodied improved arrangements 30 for water-cooling the parts.

Figures 1 and 2 on the accompanying two sheets of explanatory drawings are vertical sections at right angles to each other showing an illustrative example of the improved 35 piston and piston-rod.

As shown in the drawings, the piston-rod A has formed on its upper end and adjacent to the under side of the piston, which is made in two portions A¹, A², a double conical enlargement A³, the lower part of which 40 is of substantially the same contour as the cylinder cover, while the upper part carries a screwed tail piece B by means of which and a nut B¹ it is secured in a recess formed in the lower or skirt portion A² of the piston. The upper portion A¹ of the piston has at the bottom an inwardly projecting flange C, resting on a flange C¹, formed on the top of the lower portion A² of the piston. The 45 two parts of the piston are secured together by studs D engaged by nuts D¹ inserted in recesses D² in the piston walls. The enlargement A³ of the piston-rod A has formed through it an aperture E forming 50 a supplementary combustion space, and a fuel-injection device E¹ (shown by dotted

lines) is so positioned in the cylinder wall that fuel is delivered into the aperture E in which the combustion takes place rapidly since there is no obstruction to the passage 60 of the flame.

To permit of the circulation of cooling-water through the piston and piston-rod, the piston-rod A has in it a central longitudinal aperture F which debouches at its upper end 65 into passages F¹ formed in the wall of the enlargement A³, and passes around the combustion aperture E to the upper end of the tail piece B to which is attached a branch piece G having in it a number of hollow 70 radial arms G¹ communicating with a space H within the piston. Passages J connect the space H with the upper ends of a second series of passages K in the enlargement A³, the lower ends of which passages communicate with an annular space L between the piston-rod A and a sleeve M embracing it. The sleeve M is attached at its upper end 75 by means of flanges N on it and studs N¹ to similar flanges N² formed on the piston-rod A below the enlargement A³, while its lower end is secured in the engine crosshead. The lower end of the space L is connected 80 by means of passages P with a second annular space R surrounding a pipe R¹ carried by the piston-rod, and which communicates at its upper end with the aperture F. Preferably the cooling water flows up by the annular space L to the space H in the piston 85 and returns by the passages F¹ in the enlargement A³, and the aperture F in the piston-rod A. 90

What I claim is:—

1. In an internal combustion engine, a piston cylinder, a piston working therein and having an associated part shaped to the internal contour of the cylinder cover, said part being apertured to afford an internal combustion space when the piston is at the end of its stroke, substantially as described. 95
2. In an internal combustion engine, a piston cylinder, a piston working therein, a piston rod connected to said piston and having, adjacent the piston, a part shaped to the internal contour of the cylinder cover, 100 said part being apertured to afford an internal combustion space when the piston is at the end of its stroke, substantially as described. 105
3. In an internal combustion engine, a piston cylinder, a piston working therein, a piston rod connected to said piston and 110

2
having, adjacent the piston, a double-cone
enlargement shaped at one end to the inter-
nal contour of the cylinder, and at its other
end to a counterpart recess in the piston end,
5 said enlargement being apertured to afford
an internal combustion space when the pis-
ton is at the end of its stroke, substantially
as described.

4. In an internal combustion engine, a
10 piston cylinder, a piston working therein
and having an associated part shaped to the
internal contour of the cylinder cover, said
part being apertured to afford an internal
combustion space when the piston is at the
15 end of its stroke, in combination with water-
cooling passages extending through the pis-
ton rod and piston, and passing around said
apertured part in proximity to the combus-
tion space therein to cool the latter.
- 20 5. In an internal combustion engine, a
piston cylinder, a hollow piston working
therein, a piston rod connected to the piston
and having, adjacent the piston, a double-
core enlargement shaped at one end to the
25 internal contour of the cylinder and at its

other end to a counterpart recess in the pis-
ton end, said enlargement being apertured to
afford an internal combustion space when
the piston is at the end of its stroke, in com-
bination with a water-cooling system for the 30
piston comprising a central longitudinal
passage in the piston rod, communicating
passages in the double-cone enlargement at
the end of said rod, radial distributing pas-
sages leading therefrom and conducting the 35
cooling fluid to and from the interior of the
piston, a sleeve spaced around the piston rod
and affording an annular passage, means for
establishing connection between the latter
and the interior of the piston, a pipe form- 40
ing a continuation of the central longitudi-
nal passage in the piston rod, but affording
an annular passage around the same, and
a passage establishing communication be-
tween the interior of the piston rod sleeve 45
and said annular passage around the pipe,
substantially as described.

In testimony whereof I have signed my
name to this specification.

JOHN CAMPBELL MACCALL MACLAGAN.
